(57) **CLAIM**

The ornamental design for a temple attachment for eyewear.

DESCRIPTION

FIG. 1 illustrates a front view of a temple attachment for eyewear;

FIG. 2 illustrates a rear view of the temple attachment for eyewear; and,

FIG. 3 illustrates a front view of a temple attachment for eyewear.

The broken lines showing of the eyewear in FIGS. 1-3 are for the purpose of depicting the temple attachment to be attached on the eyewear and forms no part of the claimed design.

1 Claim, 3 Drawing SheetsFIG. 1

FIG. 2

FIG. 3
